(57) **CLAIM**

The ornamental design for a belt clip, as shown and described.

DESCRIPTION

FIG. 1 is a perspective view showing our new design;

FIG. 2 is a left side elevational view thereof;

FIG. 3 is a bottom plan view thereof;

FIG. 4 is a top plan view thereof;

FIG. 5 is a left end elevational view thereof;

FIG. 6 is a right end elevational view thereof; and,

FIG. 7 is a perspective view of our design used with a medical magnet.

The right side elevational view is identical to the left side. The medical magnet shown in broken lines is for illustrative purposes only and forms no part of the claimed design.
